UNITED STATES PATENT OFFICE.

WILLIAM A. WENZEL AND GEORGE J. RANDLE, OF PHILADELPHIA, PENNSYLVANIA.

MATRIX-CLEANING MACHINE.

Application filed October 27, 1924. Serial No. 746,002.

Our invention relates to a new and useful machine for cleaning the various surfaces of the metallic matrices commonly employed in linotype machines, intertype machines, and other similar type setting machines which cast type slugs, and it relates more particularly to a machine adapted to clean each of the six surfaces of such matrices by positive means, such as buffer rollers acting on pairs of opposite surfaces in succession.

The matrices commonly used in linotype machines and the like, very frequently become corroded and clogged with foreign matter on the surfaces thereof, so as to make the further use of these matrices impracticable and difficult. Matrices of this character have heretofore been cleaned manually and individually, that is each piece separately, and each surface thereof cleaned individually by means of a brush, and a cleaning solution. This involved considerable expense and time, and hence added greatly to the cost of operating the linotype machines, since as a rule the matrices had to be cleaned after every second or third operation.

By our novel machine we eliminate the manual cleaning of these matrices, which are used so extensively and in such large quantities in the linotype industry, and provide means whereby such matrices may be cleaned quickly and cheaply and in an automatic manner without the use of any manual labor, other than that required to feed the matrices to the machine and remove the same in the cleaned condition.

With the above ends in view, our invention consists of three pairs or sets of buffer rollers rotatably mounted with proper relation to each other, driven positively through suitable means and adapted to encounter successively the side edges, the end edges, and finally the opposed flat surfaces of the individual matrices, and means to positively feed said matrices through and between said successive sets or pairs of buffer rollers, and means to remove the same into a receiving chamber in the cleaned condition.

Our invention further consists of a novel shifting mechanism adapted to change the direction of travel of the matrices so as to pass the same through and between the last set of buffer rollers so as to clean the flat surfaces thereof.

For the purpose of illustrating our invention we have shown in the accompanying

drawings forms thereof, which are at present preferred by us, since they have been found in practice to give satisfactory and reliable results, although it is to be understood that the various instrumentalities of which our invention consists, can be variously arranged and organized and that our invention is not limited to the precise arrangement and organization of these instrumentalities as herein shown and described.

Fig. 1, represents a plan view of a matrix cleaning machine embodying our invention.

Fig. 2, represents a section on line 2—2

Fig. 1.

Fig. 3, represents a section on line 3—3 of Fig. 1.

Fig. 4, represents a front elevation of the machine.

Fig. 5, represents a right side elevation of the machine.

Fig. 6, represents a left side elevation of the machine.

Fig. 7, represents a section on line 7—7 of Fig. 6, and

Fig. 8, represents a sectional view on an enlarged scale of an auxiliary extension shaft.

Fig. 9, represents a section on line 9—9, Fig. 8.

Referring to the drawings:

1 designates an elongated receiving pan extending the length of the machine, and having a bottom 2 and side walls 3 and 4, into which pan the matrices are originally placed in the condition in which they are received from the linotype machines. 5 designates a pusher or feeding ram, carried by the ram rod 6 passing through the end wall 7 of the receiving pan 1, and having a helical tension spring 8 operatively interposed between the end 9 thereof and the wall 7, urging said ram 5 forward, in the direction of the arrow 16 shown in Figure 1. The matrices are placed in the receiving pan 1 edgewise, in front of the ram block 5, by withdrawing the ram 5 against the tension of the spring 8, and placing the matrices 11 as shown in Figures 1 and 2, with the type face downwardly. When the space between the ram, in the withdrawn position, and the first set of edge buffers 12 and 13, is filled, the machine is ready for operation. In order to permit the filling of the receiving pan 1 more readily and without interference by the buffer rollers 12 and 13, there is provided a shutter 14 adapted to slide in

through the wall 3, in the receiving pan 11 thereby retaining the matrices stationary against the tendency of the ram block 5 to force the same in between the buffer rollers 12 and 13. When the machine is thus ready for operation the slide 14 is withdrawn into the position shown in Figure 1. The buffers 12 and 13 revolve against the oncoming matrices 11 as indicated in Figures 5 and 6, and are driven through suitable gears as will be described hereinafter.

Each of the side edge buffer rollers 12 and 13 has three buffing surfaces 15, 16 and 17; the surfaces 15 and 16 adapted to engage, buff and clean the toes 18 and ears 19 of the matrices, while the buffing surfaces 17 are adapted to engage and clean the depressed portions 20 of the edges of the matrices, between said toes 18 and ears 19.

The buffer roller 12 cleans the upper toes and ears 18 and 19, as well as the depressed portion 20 between the same, while the lower buffer roller 13 buffs and cleans the corresponding lower toes and ears 18 and 19, and the type edge 21, leaving, however the type face proper 22, unaffected by the buffing action, thereby avoiding any wear, abrasion or injury of the type face 22. In order to permit a slight adjustment of the relative distance between the upper and lower side edge buffer rollers 12 and 13, so as to take care of any slight wear on said buffers, one of the buffer spindles 23 and 24, preferably however the upper spindle 23, is mounted in adjustable bearing blocks 25 and 26, and is provided with adjustment screws 27. As the buffers 12 and 13 wear and thereby increase in diameter, the slight wear may be readily taken up by simply lowering the bearing blocks 25 and 26, by means of the adjustment screws 27.

The buffer rollers 12 and 13, carried on the spindles 23 and 24 respectively, are driven by means of parallel vertical shafts 28 and 29 and corresponding pairs of bevel gears 30 and 31; the vertical shafts 28 and 29 being in turn driven through the horizontal shafts 32 and 33 through similar bevel gears 34 and 35. The horizontal shafts 32 and 33 are driven from a common main driving shaft 36, through the bevel gears 37 and 38. The main driving shaft 36, extending transversely across the machine, as shown particularly in Figures 1 and 4, is provided with a pulley 39 adapted for belt drive, as well as with a crank handle 40, adapted for the manual operation of the machine. The main drive shaft 36 is supported in a pair of suitable bearing blocks or frame members 41 and 42, while the buffer rollers 12 and 13 and the corresponding vertical drive shafts 28 and 29 are supported by a vertical frame member 53 which also supports the receiving pan 1, as shown particularly in Figure 2.

In order to effectively buff and clean the end edges 44 and 45 of the matrices, we provide a set or pair of end edge buffers 46 and 47 respectively, mounted or carried by the vertical buffer spindles 48 and 49, rotatably mounted in the hangers or bearings 50 and 51, and carried by the frame members 43 and 52 respectively. The spindles 48 and 49 are driven in the direction of the arrows 53, also against the oncoming matrices, shown particularly in Figure 1, by means of the bevel gears 54 and 55, from the horizontal drive shafts 32 and 33 described hereinbefore. The matrices, having passed through the two sets of buffer rollers 12 and 13, and 46 and 47 respectively, due to the action of the ram 5, are now ready to be buffed and cleaned on the flat surfaces thereof. In order to permit the buffing of the flat surfaces by passing the individual matrices through and between the buffer rollers 54 and 55, it is necessary to change the direction of motion of the matrices, at a right angle to the original movement thereof, namely it is necessary to remove each matrix individually from the aligned stack or group being fed forward in the receiving pan 1, and to feed said individual matrix transversely across the machine and through and between the buffering rollers 54 and 55. This individual transverse feeding movement of each individual matrix, is accomplished by means of a shifting mechanism to be described hereinafter, adapted to engage each individual matrix successively, in the order or sequence in which they are moved forward in the pan 1, to remove such individual matrices from the group or stack in the receiving pan 1, to positively feed and slide said individual matrices through the buffer rollers 54 and 55 revolving counter to the movement of the matrix, in the direction of the arrow 56 shown in Figure 1, and to move the matrix thus engaged, into the second or delivery pan 57, parallel to the pan 1 where the cleaned matrices are gathered for subsequent removal.

The surface buffers 54 and 55 carried by the spindles 58 and 59, are rotatably mounted in the stationary bearing block 60, and the floating or movable bearing block 61, carried by the sliding arms 62, and slidably secured to the stationary bearing block 60, by means of the studs 63 sliding within the guide slots 64. The floating bearing block 60 is also yieldably engaged by a helical tension spring 65, extending between and secured to the stationary bearing blocks 60 and said floating block 61, to thereby yieldably draw and urge said floating bearing block 61, and hence the floating surface buffer roller 54 towards the stationary bearing blocks 60, and hence toward the stationary buffer roller 55.

The purpose of the floating bearing block

61, and the corresponding floating surface buffer roller 54, is to provide a variable clearance between the two buffer rollers 54 and 55, so as to take care of the matrices of varying thicknesses, such as are encountered in linotype machines, namely to take care of the matrices of the various letters of the alphabet, which must necessarily be of different thicknesses depending on the particular letter.

The surface buffer rollers 54 and 55 are driven by means of bevel gears 66, 67, 68 and 69 respectively. The spindle 59, through the bevel gears 68 and 69 is driven directly from the horizontal shaft 33, while the spindle 58, through the bevel gears 66 and 67, is driven from an auxiliary horizontally extending shaft 70, rotatably mounted in the bearing block 52, and driven from the horizontal shaft 33 by means of the spur gears 71 and 72.

The auxiliary shaft 70 is split, as shown in Figure 8, the two ends 73 and 74 being connected by means of a sleeve 75, which is fixedly secured to the end 74, and slides freely on the squared end 73, as indicated in the sectional view in Figure 9.

The helical compression spring 75 is interposed between the two ends 73 and 74, so as to urge the end 73 forward in the direction of the arrow 77, thereby forcing the bevel gear 66 into engagement with the movable or floating bevel gear 67, carried by the movable floating spindle 58. As the movable or floating bearing 61 and buffer 54, oscillate to and fro a slight amount, to take up the difference in the thickness of the various matrices, the bevel gear 66 follows the bevel gear 67, urged by the compression spring 76.

The shifting mechanism mentioned hereinbefore provided for the purpose of removing the individual matrices from the receiving pan 1, at a right angle to the original line of travel, consists chiefly of the vertical movable finger 78, shown particularly in Figures 3, 5 and 6, carried by the horizontally extending arm 79 forming part of the vertical slide 80, which is slidably mounted in dovetailed slides or guides 81 and 82. The dovetailed vertical slide 80, supported by the guides 81 and 82, is in turn carried by the horizontal sliding carriage 83, mounted for transverse sliding movement or travel, on the guide way 84, as shown in Figures 5 and 6. The horizontal transverse carriage 83 is provided with guides 85 and 86 rigidly secured thereto or formed integral therewith, which are adapted to travel in the guide slots or runways 87 and 88 respectively. The bearing block or frame member 42 also carries a shaft 89, which is driven from the main driving shaft through the bevel gears 90 and 91. The shaft 89 carries at the front extremity thereof, a cam wheel 92, having a peripheral camming surface 93, on one por-

tion of the periphery thereof, and carrying a crank pin 94, properly located on said cam wheel with respect to the cam surface 93. The connecting rod 95, mounted on the crank pin 94 at one end, and on the pin or stud 96, carried by the transverse horizontal carriage 83, at the other end thereof, so interconnects the crank pin 94 with the horizontal transverse carriage 83, as to give said transverse carriage 83, and hence the vertical slide 80 and finger 78, a reciprocating transverse movement or travel, between the two pans 1 and 57 respectively.

The vertical slide 80, urged downwardly by the helical tension spring 97, is adapted to be raised periodically by a cam 98, pivotally mounted at 99, on the transverse carriage 83. The cam 98 is provided with an eccentric cam surface 100, and is normally in the horizontal position shown in Figure 4, with the lower edge 101 of the vertical slide 80, resting against the edge 102 of said cam. When the transverse carriage 83 is drawn to the extreme right position of its travel (Figure 4) by the crank pin 94 and connecting rod 95, the inclined edge 103 of said cam 98, encounters a correspondingly inclined edge 104 of a stationary cam 106, fixed to the frame of the machine, as shown in Figure 4, thereby deflecting the edge 103 downwardly so as to revolve the cam 98 clockwise into a vertical position, thereby causing the eccentric camming surface 100 to raise the vertical slide 80 into its upper position, against the tension of the spring 97.

When in this raised position the finger 78 (Fig. 3) is clear of the top of the toes and ears 18 and 19, of the matrix 11. Due to the flat portion of the cam surfaces 100, the slide 80 resting against said straight or flat portion, is retained in the raised position, until the transverse carriage or slide 83 travels back to the extreme left position of its path of travel, in which position the finger 78 is above and in vertical alignment with the central portion 20 of the matrix in the receiving pan 1. When, however, the transverse carriage 83 reaches the extreme left position of its travel, the edge 107 encounters a second stationary cam 108 having an inclined edge 109, which again deflects the cam 98, revolving it counterclockwise into the horizontal position, thereby lowering the vertical slide 80 and hence the finger 78, into the position shown in Figure 3, where finger 78 rests on the depressed edge portion 20 of the matrix 11. In this lowered or engaged position of the finger 78, the transverse slide 83 is withdrawn by the crank pin 94, to the right, causing it to carry with it the matrix 11 so engaged, and thereby forcing said matrix through and between the two buffer rollers 54 and 55, into the delivery pan 57. Thus the cycle of operations of the transverse slide 83 and

the vertical slide 80 is repeated with each revolution of the cam wheel 92.

In order to aid the removal of the individual matrix from the receiving pan 1, through the buffer rollers 54 and 55, into the delivery pan 57, by means of the shifting finger 78, there is provided an ejector blade 110 shown in Figs. 1 and 4, slidably carried in a bracket 111, and adapted to slide into the receiving pan 1 a slight distance, so as to force the last matrix 11 from the oncoming stack of matrices. The ejector blade 110 is sufficiently thin so as to engage no more than one matrix at a time, namely it is slightly thinner than the thinnest matrix, which would probably be the matrix corresponding to a period or a comma. The ejector blade 110 is actuated in proper synchronism with the cycle of events of the shifting finger 78, by means of the cam 93 acting on a follower roller 112 carried by a pivotally supported arm 113, pivoted to the frame at a point 114, and tensioned by the helical tension spring 115. The connecting rod 116 is secured at one end thereof to the ejector blade 110, at a point 117, while the other end thereof is secured to the extremity of the arm 113, at the pivot point 118. Thus with each revolution of the cam wheel 92, revolving in the direction of the arrow 119 (Figure 4), the camming surface 93 encounters the follower roller 112, moves the same against the force of the spring 115, thereby forcing the ejector blade 110 into the receiving pan 1, so as to force and tend to remove the last of the matrices in said pan through the exit aperture 120 in the side wall 4 of said pan, provided for that purpose. The shifting finger 78 in the meantime engages the said matrix, and completes the shifting of said matrix from the receiving pan 1 to the delivery pan 57, through the two rollers 54 and 55.

In order to move the matrices forward in the delivery pan 57 in the direction of the arrow 121 away from the entrance aperture 128 with each stroke of the machine, so as to make room for the entrance into said delivery pan 57 of the next matrix; there is provided a jogger 122 in the fore end of said delivery pan 57, consisting of the jogger block 122, a stem 123, and a compression spring 124, said spring urging said jogger block 122 in the direction of the arrow 121. A cam 125 is fixed rigidly to the transverse carriage 83 as shown in Figs. 1 and 4, and is provided with the inclined cam edge 126 in alignment with the head 127 of the stem 123 of said jogger 122. Thus in the normal position shown in Fig. 1, the spring 124 moves said jogger forward in the direction of the arrow 121, to the limit of its movement. When, however, the transverse carriage 83 moves towards the right, carrying with it the matrix which is about to enter

the delivery pan 57 through the entrance aperture or opening 128, the inclined cam 126 engages the head 127 on the jogger stem 123, and withdraws the same against the tension of the spring 124 so as to permit the entrance of the matrix 11, through said aperture 128. When the carriage 83 is moved to the left again, leaving behind the matrix 11 in the delivery pan 57, the jogger 122, urged by the spring 124 moves forward a slight distance again in the direction of the arrow 121, thereby moving up the group or stack of matrices in said delivery pan 57, so as to provide room for the entrance of the next succeeding matrix. 80

The receiving pan 1, is also provided with the jogger 130, at the fore end thereof, for the purpose of imparting a slight vibratory movement to the stack of oncoming matrices in said receiving pan 1, so as to loosen or free the individual matrices from one another, thereby to facilitate the removal of the individual matrix from said group in the receiving pan 1. The jogger 130 is also provided with a stem 131, and a compression 90 spring 132 interposed between the head 133 thereof and the wall of the receiving pan 1. The cam 125 carried rigidly and fixedly on the transverse carriage 83, is provided with a slight camming projection 134, in alignment with said head 133, and adapted to encounter said head 133 when the transverse carriage is moved to the left, thereby to force said jogger 130 forward in the direction of the arrow 121 a slight distance, so as 100 to impart a slight jarring action to the whole group of matrices in the receiving pan 1.

The buffer wheels 11 and 12, 46 and 47, and 54 and 55 may be made of any suitable 105 material and may be of any suitable construction, such as soft brushes, cloth, but are preferably made of a soft felt. The cleaning of the matrices may be accomplished with the buffer alone, or if desired a suitable cleaning solution may be used in combination with the buffers. 110

Thus by our novel matrix cleaning machine the matrices may be cleaned throughout their various surfaces without any manual labor, other than that required to supply the matrices to the machine and to remove the same in cleaned condition, and the cleaning is effected moreover without any damage or injury to the type faces or the 120 selector contours of the matrices. 115

Having thus described our invention what we claim as new and useful and desire to secure by Letters Patent, is:—

1. In a device of the character stated, a 125 pair of side edge buffer rollers, a pair of end edge buffer rollers at right angles thereto, a pair of surface buffer rollers, means to guide matrices through the first two pairs of buffer rollers, means to urge said mat- 130

- rices through said first two pairs of buffer rollers, and means to guide and pass said matrices through the last pair of surface buffer rollers.
5. In a device of the character stated, a receiving pan, a delivery pan, a guide way disposed at a right angle to said pans, transverse carriage slidably mounted on said guide way, a vertical slide, slidably mounted on said transverse carriage, a shifting finger carried by said vertical slide, a pivoted lifting cam carried by said transverse carriage in operative alignment with said vertical slide, means to move said transverse carriage to and fro between the receiving and delivery pans, and stationary cams carried by the guide way at each extreme position of the travel of said transverse carriage, adapted to lift said vertical slide and said shifting finger when said finger has reached the limit of said travel towards the delivery pan, and to lower said slide and said finger when said finger has reached the limit of its travel towards the receiving pan.
10. In a device of the character stated, a pair of side edge buffer rollers, a pair of end edge buffer rollers at right angles thereto, a pair of surface buffer rollers, means to guide matrices through the first two pairs of buffer rollers, means to urge said matrices through said first two pairs of buffer rollers, and means to guide and pass said matrices through the last pair of surface buffer rollers individually.
15. In a device of the character stated, a receiving pan, a pair of side edge buffer rollers rotatably mounted above and below said pan, a pair of end edge buffer rollers rotatably mounted and adjacent to the sides 20 of said receiving pan, a delivery pan, means to shift individual matrices from the receiving pan to the delivery pan, and a pair of surface buffer rollers located between said two pans and adapted to buff the surfaces of 25 the individual matrices passing from one pan to the other.
4. In a device of the character stated, a receiving pan, a delivery pan, a shifting finger slidably mounted for transverse movement relative to said pans, means to move said shifting finger to and fro between said pans, means to raise and lower said shifting finger in synchronism with the shifting movement of said shifting finger, and an 30 ejector cooperating with said shifting finger to remove the individual matrices from said receiving pan.
35. In a device of the character stated, a receiving pan, a delivery pan parallel thereto, an exit opening in said receiving pan, and an entrance opening in said delivery pan in alignment with each other, a pair of buffer rollers located between said pans, and in operative alignment with said exit and entrance openings, and means to feed matrices to said exit opening in said receiving pan, and a jogger in said delivery pan adapted to move the matrices away from the entrance opening and means carried by said transverse carriage adapted to actuate said joggers periodically.

WILLIAM A. WENZEL.
GEORGE J. RANDLE.
